TANK WASHING APPARATUS

William Ostling, Los Angeles, Calif., assignor to
The Pyrate Corporation of Nevada, a corpora-
tion of Nevada

Application February 8, 1935, Serial No. 5,600

18 Claims. (Cl. 299—68)

This invention has to do in a general way with devices for cleaning tanks and the like, and it is more particularly related to improvements in devices of the general type disclosed in application Ser. No. 637,028, filed jointly by Clare Richard and Harold M. Ruth on October 10, 1932, application Ser. No. 672,927, filed by Harold M. Ruth on May 26, 1933, and application Ser. No. 734,937 filed by Clare Richard on July 13, 1934, all of said 10 applications being assigned to the assignee in the present case.

The apparatus contemplated by this invention, like the devices disclosed in the three applications referred to above, is especially adapted for use in washing the tanks on tank cars and in oil tankers of their remaining contents subsequent to draining. The general construction of these devices embodies a stationary vertical feed pipe which is suspended through the top of the tank 15 by suitable means positioned over the tank opening. This feed pipe carries, on its lower end, a rotatable secondary feed pipe or housing adapted to rotate about a vertical axis, such housing being provided with a nozzle member which is 20 mounted for rotation about its substantially horizontal axis. Means are provided for rotating the nozzle member about its horizontal axis during the passage of a washing fluid therethrough and additional means are provided for effecting a 25 segmental step by step rotation of the housing which carries the nozzle member about its vertical axis during the rotation of the nozzle member.

It is an important feature of the device contemplated by this invention, like those of the other applications referred to above, that the housing is held stationary during a substantial period in the rotation of the nozzle member. Such period of rest in the housing is preferably 30 sufficient to effect a complete cleaning action on a peripheral circle of the tank surface by the nozzle, before the housing is moved.

In cleaning the tanks on tank cars, the washing unit is ordinarily suspended in the center of 35 the tank car, and, since the cars are much longer than they are wide, it will be apparent that a given angular increment of motion in the housing, while the nozzles are directed toward the ends of the car, will cover a much greater distance at the end of the stream than will be covered 40 while the nozzles are directed toward the sides of the car. This invention, like those described above, therefore, contemplates means for varying the increment of angular movement in the housing during such times as the nozzles are 45

directed towards the sides and towards the ends of the car, respectively.

The nozzle unit in this invention, like that disclosed in the Ruth application and the Richard application referred to above, is adapted to be 5 driven by a liquid turbine mounted on the housing.

It is a primary object of this invention to produce a washing device of the class described which is provided with improved means for effecting the 10 segmental or step by step rotation of the housing upon the stationary feed pipe. In this connection, my invention contemplates means which are positively actuated from the nozzle member and which are enclosed to protect the mechanism from 15 the action of the washing fluid.

My invention further contemplates an improved means for varying the increment of rotation of the housing during the operation of the unit for the purpose and in the general manner 20 referred to above. In this same connection, my invention contemplates improved means for effecting an adjustment of the increments just referred to.

It is another important feature of this invention that I have improved the construction of the 25 nozzle assembly which materially facilitates the dismantling of the unit for cleaning and inspection purposes and which is also designed to materially reduce the loss in velocity of the liquid as 30 it passes through the nozzle unit.

It is a still further improved feature of this invention that I provide novel means for effecting lubrication of the turbine shaft, such means being substantially enclosed within the housing 35 unit so as to be afforded protection during the handling of the machine.

It is a still further object of this invention to provide a device of the class described which is of compact construction and in which the moving parts have a minimum of frictional loss. Further, that all of the moving parts are substantially enclosed in suitable housings whereby the liability of damage due to handling or due 40 to contact with the washing liquid is reduced to 45 a minimum.

Details in the construction of a preferred form of my invention, together with other objects attending its production, will be best understood 50 from the following description of the accompanying drawings, which are chosen for illustrative purposes only, and in which

Fig. 1 is an elevational view partly broken away and showing a preferred form of device contem- 55

plated by this invention as being suspended through the opening in the top of the tank;

Fig. 2 is a fragmentary elevation showing the side of the machine opposite to that which is illustrated in Fig. 1;

Fig. 3 is an enlarged sectional elevation taken in the plane represented by the line 3—3 of Fig. 2;

Fig. 4 is a sectional elevation on the line 4—4 of Fig. 3;

Fig. 5 is a sectional elevation on the line 5—5 of Fig. 3;

Fig. 6 is a sectional elevation substantially along the line 6—6 of Fig. 3, parts in Fig. 6 having been shown in front of the section plane;

Fig. 7 is an inverted plan view which may be considered as having been taken substantially along the line 7—7 of Fig. 3;

Fig. 8 is an enlarged sectional elevation along the line 8—8 of Fig. 2; and

Figs. 9 and 10 are diagrammatic elevations with parts in section illustrating the operation of the means for controlling the increments of movement of the housing on the stationary feed pipe.

More particularly describing the invention as herein illustrated, reference numeral 11 indicates the top of the tank, or tank dome as the case may be, which is provided with an opening 12. Numeral 13 indicates a cover plate adapted to fit over the opening 12 and is held in place by any suitable locking means such as is indicated by reference numeral 14. The cover plate 13 is provided with an opening 15 which receives and supports in any suitable manner what I may term a main feed pipe generally indicated by reference numeral 16. The main feed pipe 16 is adapted to be suspended downwardly into the tank, and the lower end of such pipe carries what I may term a rotatable housing and nozzle assembly unit generally indicated by reference numeral 17.

That portion of the main feed pipe 16 below the cover 13 is shown as being surrounded by a sleeve, generally indicated by reference numeral 19, the lower end of which supports a conical deflecting member 20 adapted to deflect washing liquid from the nozzle unit into the dome of the tank car. Immediately below the deflecting unit the sleeve 19 is provided with a ring member 21 which is provided with handles 22 to facilitate handling the unit.

The top of the main feed pipe is shown as being provided with a T-fitting 23, such T-fitting having a stirrup 24 thereon for use in lowering the unit into a tank. The upper opening of the T-fitting is provided with a packing member, not shown, through which an oil delivery pipe 25 rotatably extends, such pipe having an oil cup 26 on its upper end. The arm 28 of the T-fitting receives a suitable conduit 29 which is used to deliver washing liquid into the main feed pipe 16.

For convenience in the manufacture and assembly of the unit I prefer to make the main feed pipe 16 in two sections connected together by a flange fitting indicated by reference numeral 35. For the purpose of this description, however, the feed pipe may be considered as a single piece and the lower section 16a will therefore be referred to in the description as the main feed pipe. It will appear from Fig. 8 that the main feed pipe 16a is provided with an elongated flange 36 which is shown as having a worm gear 37 formed or otherwise secured thereon. The purpose of the worm gear will be described later in the specification, but it should be pointed out at this time that such worm gear need not neces-

sarily be an integral part of the flange but may be a separate member suitably secured to the stationary feed pipe.

The housing and nozzle assembly unit 17 includes what I may term a main housing generally indicated by reference numeral 39, such main housing having an upwardly extending sleeve portion 40 which receives the lower end of the stationary feed pipe 16a. The top of this sleeve portion 40 is formed in the nature of a bell 42, such bell surrounding the elongated flange and gear 36 and 37, respectively. The upper end of the bell 42 receives an externally threaded ring 43 which rests upon ball bearings 44, such bearings in turn resting on the upper shoulder formed by the flange 36. In this way the housing assembly is rotatably mounted on the lower end portion of the main feed pipe 16a. The ring 43 is provided with upstanding lugs 44' adapted to receive a spanner wrench for use in assembling the unit and the ring is adapted to be locked in place by means of an angle member 46 which extends between two of the lugs 44' and is secured to the face of the bell by means of screws 48.

The bottom of the bell is formed with a shoulder 50 which supports the bottom ring element 51 of a seal unit which consists of an upper flanged ring 52 having sliding engagement with the bottom of the elongated flange 36, the rings 51 and 52 being yieldably held in spaced relation with each other by means of springs 53. (See Fig. 8). Near the lower end of the sleeve 40 I provide a shoulder 54 which supports a packing ring 55, engaging the lower end of the feed pipe 16a, such packing ring co-operating with the seal members 51 and 52 to afford a substantially leak-proof assembly.

The bottom of the main housing 39 is formed with an enlarged chamber 56 which I have termed a nozzle receiving chamber. This chamber 56 is provided with openings 57 and 58 in the sides of the housing and on an axis which is transverse to the axis of the main feed pipe and the general axis of rotation of the housing (see Figs. 3 and 6). For this reason I will describe the nozzle housing 56 as being a transverse housing with openings in the side faces thereof.

Reference numeral 59 indicates what I may term a bushing or cage member which is mounted in the nozzle housing 56 through the openings 57 and 58. This bushing member 59 has a flange 60 which fits within a suitably shaped recess formed on one face of the housing member about or adjacent to the opening 58 and the other end of the bushing member is threaded as indicated at 62 to receive a spanner nut 63 which is adapted to co-operate with the flange 60 to lock the bushing member in place. The spanner nut is held in a predetermined position by means of a set screw 64. That portion of the bushing member which is situated within the housing proper is provided with what I may term an enlarged chamber 66, the wall of which is formed with ports 67. The bushing or cage member just described constitutes the bearing for a nozzle member generally indicated by reference numeral 70 and its construction is such that by removing the spanner nut 63 the nozzle assembly with all its associated parts may be separated from the main housing.

The nozzle member 70 is shown as comprising a pair of radially diverging arms 71 and 71', the outer ends of which are provided with nozzles generally indicated by reference numeral 72.

These nozzle arms 71 and 71' are formed integrally with a hollow spindle 73 which is rotatably mounted in the bushing 59. The end of the hollow spindle 73 opposite the nozzle member is provided with a closure generally indicated at 74 and that portion of the hollow spindle which is situated within the enlarged chamber 66 and bushing is provided with wall ports generally indicated by reference numeral 75. A pin 77 is formed on the closed end of the hollow spindle, such pin extending through a packing ring 78 provided in an opening through what I may term a bearing cap 79. This bearing cap 79 is secured by means of screws 80 to the face of the bushing 59 and is provided with an undercut portion 81 which receives a radial-thrust bearing 82. A nut 83 is threaded on the end of the pin 77 in engagement with one runner of the radial-thrust bearing, so it will be seen that this bearing receives the thrust of the nozzle unit during its operation. A cap 85 is mounted over the opening through the cover member 79, such cap being provided with a grease fitting 86 for lubricating the radial-thrust bearing. A spring pressed liquid seal assembly, generally indicated by reference numeral 90, is mounted upon the end of the hollow spindle 73 around the pin 77 and is contained within a recess 91 formed in the end of the bushing. This recess is provided with a drain opening generally indicated by reference numeral 92.

That portion of the hollow spindle 73 which carries the nozzle 71 and 71' extends a substantial distance beyond an extending portion 97 on the bushing so as to leave space for the reception of another pair of seal rings generally indicated by reference numeral 98. The diameter of the nozzle member at this section is then increased to form an annular shoulder 99 which supports the outer edge of what I may term a cam collar 100 which is secured to the nozzle member by means of screws 101. This cam collar 100 is provided with a cam flange indicated at 102, the purpose of which will be hereinafter more fully described, and that portion of the collar opposite the cam extends inwardly to a point above the extension 97 on the bushing where it is provided with an underhanging annular lip 104 which provides a recess for the reception of the ball bearing 105. Reference numeral 106 indicates a grease duct which communicates with the bearing 105 and is provided with a suitable grease fitting 106' mounted on the outer face of the nozzle member.

The periphery of the inner end of the collar 100 is cut away as indicated at 107 to receive a floating gear 108. This floating gear 108 has recesses 111 formed therein, such recesses receiving pawls 112 which are supported on pins 113 and are pressed inwardly by means of springs 114 toward their ratchet teeth 115 which are cut on the periphery of the collar member 100 at its inner end (see Fig. 5).

The gear 108 has worm gear teeth 120 cut on its periphery, such teeth being adapted for engagement with a worm 121 which is mounted on the end of a shaft 122. This shaft 122 is carried by bearings 123 and 124 contained within a projection 125 on a housing 126 which is secured to a face plate 127 of the main casting or housing 39 by means of screws 128. The housing 126 is provided with a cover plate 130 and is mounted over an opening in the face plate 127 which communicates with the interior of what I may term a turbine shaft boss 132. The other end of the

shaft 122 is provided with a worm gear 138 which is secured to the shaft by means of a suitable key and is held in place by a nut 139. The worm gear 138 engages with a worm 141 which is keyed to the extending end of a turbine shaft 142 generally indicated by reference numeral 142. The turbine shaft 142 extends through the turbine shaft boss 132 and is supported therein by means of bearings 143 and 144. The bearing 144 is shown as being held in place by means of a collar 145 secured through the medium of screws 146 to the face of a turbine wheel guard plate 147 which is also shown as being formed integrally with the main casting or housing 39. The other end of the turbine shaft 142 is provided with a nut 150 which engages the worm 141. On the end of the shaft opposite the worm 141 I provide a turbine wheel 153 which is keyed to the shaft and is held in place by means of a nut 154.

It is a feature of this invention that the turbine wheel is driven by the same pressure fluid which is delivered into the housing for washing purposes, and for the purpose of directing such pressure fluid against the vanes of the turbine wheel I provide the housing with what I may term turbine nozzle feed chambers indicated by reference numeral 160 and 160' (see Figs. 2 and 6). The chambers 160 and 160' have annular recesses 161 and 161' in their walls, such recesses communicating with passages 162 and 162' which lead to transverse passages 163 which carry the turbine nozzle members 164 and 164'.

The turbine nozzle feed chambers 160 and 160' are identical except for their positions on the housing and each is provided with a cover indicated at 167 which has an inwardly extending flange 168 provided with ports 169 communicating with the annular passage 161 or 161' as the case may be. The inner edge of the flange 168 engages a screen 170 which is positioned against a shoulder 171 surrounding the opening 172 which communicates with the chamber 161 or 161'. This screen serves the purpose of straining the liquid which is to be used for the purpose of impelling the turbine.

For the purpose of insuring proper lubrication of the turbine shaft bearings 143 and 144, I provide the turbine shaft with oppositely disposed screw or worm threads which extend in opposite directions from the central portion indicated by the groove 173. The boss 132 which supports the turbine shaft is provided with an opening 173' situated opposite the groove 173, such opening containing a fitting 174 which communicates with an oil drip reservoir 174''. This drip reservoir 174'' is fed from a pipe 175, such pipe being connected at its lower end to a boss 175' on the main housing with a passage 176 formed in an enlarged boss 177 which is cast or drilled in the housing. The passage 176, in turn, communicates with a passage 177 which extends through another boss 178 formed on the housing, such passage having a fitting 178' in its lower end which is connected to a U-fitting 179 and a suitable bushing 180 with the lower end of the oil delivery pipe 25. As will be observed in Fig. 6, the lower end of the pipe 25 extends through an opening 181 in the bottom of the housing, below which an internally threaded collar 182 extends, such collar receiving a packing assembly generally indicated at 183. The U-pipe and the associated fittings are provided with a cover member 185 which is secured to a flat face 186 on the lower portion of the housing by means of screws 187.

It will be apparent from the description as de-

scribed so far that when a washing liquid under pressure is delivered into the stationary feed pipe 16a it passes downwardly therethrough into the enlarged chamber 56. From the enlarged chamber 56 part of this liquid passes into the two nozzle feed reservoirs or chambers 160 and 160' from which it is directed through the associated passages and the nozzle members 164 and 164' into engagement with the vanes of the turbine wheel. 5
10 The rotation thus set up in the turbine wheel is carried through the turbine shaft and the associated worm gears to the worm gear 108 on the collar member 100 which is secured to the nozzle member. The rotation is such as to force the 15 pawls into positive engagement with the ratchet teeth on the collar member, thereby setting up a rotation of the nozzle, and the turbine nozzles may be adjusted from right to left in order to vary the speed to obtain that which is desired 20 for the particular purpose. The bulk of the washing liquid, which is delivered into the enlarged chamber 56, passes through the ports in the bushing and the nozzle member, entering the hollow spindle of the nozzle and therefrom passes 25 directly into the diverging nozzles where it is projected into engagement with the surfaces to be cleansed.

For the purpose of protecting the gear and cam mechanism on the nozzle member, the face 30 plate 127 is provided with a projecting flange 127' which receives a correspondingly shaped cover member 195, such cover member being secured to the flange by means of screws 196. The flange 127' is provided with an opening in its bottom 35 indicated at 197 to take care of any leakage which might occur through the seals in the nozzle assembly.

It was previously pointed out as one important object of this invention to provide an improved 40 means for effecting the step by step rotation of the housing and its associated parts about the main feed pipe during the rotation of the nozzle, and it is for this purpose that the cam 102 is provided. This cam, it will be observed in Fig. 45, is provided with two diametrically disposed abrupt humps indicated at 200 and 200'. Numeral 201 indicates a push rod which is supported in a guide 202, and extends through a bossed opening 203 on the top of the cover. The lower end 50 of this push rod has a follower 204 which engages the cam and the upper end engages a head 233 on an auxiliary push rod 201'.

Reference numeral 210 indicates what I may term a box member which is preferably cast upon 55 the barrel portion of the main housing and circumscribes an opening 211 in the side of the bell adjacent the worm 37. This box member 210 is provided with a cover 212 secured thereto by means of screws 213, and the interior of the cover 60 and the box member are provided with co-operating ribs 214 which have bearing portions 215 thereon supporting a shaft member 216. (See Figs. 3 and 4). The shaft 216 carries a worm 65 217 which engages the worm gear 37. In addition to the worm 217 the shaft carries a ratchet wheel 220 and freely rotatable pawl carrier 221 which straddles the ratchet wheel.

The pawl carrier 221 is provided with a pawl 70 222 mounted on a pivot pin 223, the pawl being disposed so as to engage the teeth on the ratchet wheel and being provided with a forwardly extending weight 224 to hold it in such engagement. The bottom of the pawl carrier has an inclined face 226 which is situated above the upper end of 75 the auxiliary push-rod 201'. The push rods 201,

201' are therefore adapted to push the pawl carrier upwardly imparting a rotation to the ratchet wheel in the direction of the arrow A in Fig. 3 and, for the purpose of returning the pawl carrier to its normal position, I propose to provide the same 5 with a weighted section generally indicated at 227. The bottom of the cover member 212 is shown as being provided with an upwardly extending boss 230 which is provided with a passage for the push rod section 201'. Immediately below 10 the boss 230 on the bottom of the cover member I provide a bell 231 which fits over the boss 203 on the top of the cover 195, such bell containing a compression spring 232 which engages the head 233 on the section 201' to hold the follower in 15 pressure engagement with the cam.

It will thus be seen that during the rotation of the cam each of the humps thereon is effective to push the push rods 201—201' upwardly into engagement with the pawl carrier, thereby effecting 20 a segment of rotation in the ratchet wheel and its associated worm which in turn is effective to impart a step of rotation to the housing about its vertical axis. The extent of the rotation which is imparted to the housing in this manner depends 25 upon the position to which the pawl carrier has dropped prior to its engagement with the push rod.

I take advantage of this last mentioned fact to obtain the variations in the increment of rotation 30 for the purpose pointed out above. This is accomplished by providing the interior of the housing with a lever member 240 mounted on a pin 241 and having one end 242 thereof positioned below a projected corner 243 on the pawl carrier. The 35 end 242 of this lever member is shown as being offset downwardly from the main portion thereof and the connecting arm is shown as being slotted as indicated at 245 to receive what I may term a stop lever 246. This stop lever 246 is held in 40 its uppermost position by means of a cushion spring 249 and as the pawl carrier drops the extended portion 243 swings into engagement with the stop lever, its downward movement being cushioned by the spring. The position of the lever member 240 is governed by a connecting rod 251, the lower end of which extends through an opening 252 in the lever and is provided with an adjustable nut 253. A compression spring 255 is interposed between the lever and the top of the 50 cover 212 to hold the lever in its lowermost position. The connecting rod 251 extends through an opening in the top of the cover and has its upper end provided with a knife-edged bearing 257 which is threaded on the rod. This knife-edged 55 bearing 257 is received in notches 258 in the end of a cam operated lever 259 through which the upper end of the rod extends. This cam operated lever 259 is mounted on a pin 260 supported by standards 261 on top of the cover 212. The free 60 end of the lever 259 is provided with a cam follower 262 which engages a face cam 263 formed on a plate 264 secured by welding or in any other suitable manner to the main feed pipe 16a. It will be seen that as the follower is pressed downwardly by the action of the cam the bottom lever 240 is raised which correspondingly raises the stop member 246 as illustrated in Fig. 9 and consequently the pawl carrier is not permitted to drop over as many teeth as it is when the follower engages a depression in the cam as illustrated in Fig. 10 which permits the pawl carrier to drop to a lower position.

Relative to Figs. 9 and 10 it is to be understood from Figs. 9 and 10 that the pawl carrier and its 75

associated mechanism are illustrated as having been turned through 90° from their actual position in the machine. The shape of the cam will depend of course upon the type of tank being cleaned and the extent of the movement can be governed by varying the adjustment upon either of the nuts on the ends of the connecting rod 251. A shield 271 is shown as being mounted on top of the cover 212 for the purpose of protecting the cam lever and its associated parts.

It is to be understood that, while I have herein described and illustrated one preferred form of my invention, the invention is not limited to the precise construction described above but includes within its scope whatever changes fairly come within the spirit of the appended claims.

I claim as my invention:

1. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; and a worm gear secured to said feed pipe and engaging said worm.

2. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; yieldable means holding said push rod in pressure engagement with said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; and a worm gear secured to said feed pipe and engaging said worm.

3. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means;

and a worm gear secured to said feed pipe and engaging said worm, said cam being formed so as to impart intermittent movement to said push rod during the rotation of said nozzle unit.

4. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; a worm gear secured to said feed pipe and engaging said worm; and stop means for limiting the downward movement of said pawl carrier toward said push rod.

5. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; a worm gear secured to said feed pipe and engaging said worm; and stop means for limiting the downward movement of said pawl carrier toward said push rod, said stop means including a lever pivoted to said housing unit with one end below said pawl carrier, a cam member on said feed pipe, a second lever member pivoted on said housing unit and having one end engaging said cam, and a link interconnecting said levers.

6. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said unit in engagement with said pawl; a worm rigidly connected with said ratchet means; a worm gear secured to said feed pipe and engaging said worm; stop means below said pawl carrier for limiting the downward movement of said pawl carrier toward said push rod; and automatic means operable during the rotation of said housing unit for varying the position of said stop

means with respect to said pawl carrier at predetermined intervals.

7. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; a worm gear secured to said feed pipe and engaging said worm; stop means for limiting the downward movement of said pawl carrier toward said push rod; and a cushioning member on said stop means adapted to be engaged by said pawl carrier.

8. In a cleaning device of the class described, the combination of: a stationary feed pipe; supporting means for said feed pipe; a housing unit mounted on the end of said feed pipe for rotation about the axis of said feed pipe; a nozzle unit mounted in said housing for rotation about an axis normal to the axis of said housing; means for producing a continuous rotation of said nozzle unit about its axis; a cam member secured to said nozzle unit; a push rod slidably supported by said housing unit with one end engaging said cam; a pawl carrier swingably supported on said housing unit and adapted to be engaged by the other end of said push rod; a pawl in said pawl carrier; ratchet means rotatably supported on said housing unit in engagement with said pawl; a worm rigidly connected with said ratchet means; a worm gear secured to said feed pipe and engaging said worm; and stop means for limiting the downward movement of said pawl carrier toward said push rod, said stop means including a lever pivoted to said housing unit with one end below said pawl carrier, a stop member movably mounted in the said lever for engagement with said pawl carrier, spring means holding said stop member in elevated position; a cam member on said feed pipe, a second lever member pivoted on said housing unit and having one end engaging said cam, and link means interconnecting said levers.

9. In a cleaning device of the class described, the combination of: a stationary feed pipe having a bearing flange and a worm gear thereon; a housing member having a sleeve section provided with a bell adapted to receive said flange and gear; bearing means in the top of said bell for supporting said housing from said bearing flange; a box member formed on said housing and enclosing an opening in the side of said bell; a worm shaft mounted in said box member; a worm on said worm shaft engaging said worm gear; a ratchet member on said worm shaft; pawl means swingably supported in said box for advancing said ratchet member and said worm; a push rod slidably extending through the bottom of said box member with its upper end adapted for engagement with said pawl member; a nozzle member mounted in the bottom of said housing for rotation about an axis normal to the axis of said housing; a cam secured to said nozzle member.

and engaging the bottom of said push rod; and means for rotating said nozzle member.

10. In a cleaning device of the class described, the combination of: a stationary feed pipe having a bearing flange and a worm gear thereon; a housing member having a sleeve section provided with a bell adapted to receive said flange and gear; bearing means in the top of said bell for supporting said housing from said bearing flange; a box member formed on said housing and enclosing an opening in the side of said bell; a worm shaft mounted in said box member; a worm on said worm shaft engaging said worm gear; a ratchet member on said worm shaft; pawl means swingably supported in said box for advancing said ratchet member and said worm; a push rod slidably extending through the bottom of said box member with its upper end adapted for engagement with said pawl member; a nozzle member mounted in the bottom of said housing for rotation about an axis normal to the axis of said housing; a cam secured to said nozzle member and engaging the bottom of said push rod; means for rotating said nozzle member; and a cover member secured to said housing below said box member, said cover member having guides formed therein, slidably engaging said push rod.

11. In a cleaning device of the class described, the combination of: a stationary feed pipe having a bearing flange and a worm gear thereon; a housing member having a sleeve section provided with a bell adapted to receive said flange and gear; bearing means in the top of said bell for supporting said housing from said bearing flange; a box member formed on said housing and enclosing an opening in the side of said bell; a worm shaft mounted in said box member; a worm on said worm shaft engaging said worm gear; a ratchet member on said worm shaft; pawl means swingably supported in said box for advancing said ratchet member and said worm; a push rod slidably extending through the bottom of said box member with its upper end adapted for engagement with said pawl member; a nozzle member mounted in the bottom of said housing for rotation about an axis normal to the axis of said housing; a cam secured to said nozzle member and engaging the bottom of said push rod; means for rotating said nozzle member; and means for limiting the swinging movement of said pawl means, comprising a face cam secured to said feed pipe above said bell, a lever member engaging said face cam, pivot means on the top of said box member supporting said lever member, a second lever pivoted in said box member with an end thereof below said pawl member, and a rod extending through an opening in the top of said box member and interconnecting said levers.

12. In a cleaning device of the class described, the combination of: a stationary feed pipe; a housing rotatably mounted on the end of said feed pipe, said housing having a transverse nozzle chamber with openings in the sides of said housing; a cage member mounted in said nozzle chamber through said side openings and having wall ports communicating with the interior of said housing; a nozzle member having a hollow spindle rotatably mounted in said cage member, said spindle having wall ports communicating with the interior of said cage; means for securing said cage member in said nozzle housing; thrust receiving means for holding said nozzle member against transverse movement in said cage member; means for rotating said nozzle

spindle; and means for simultaneously rotating said housing.

13. In a cleaning device of the class described, the combination of: a stationary feed pipe; a housing rotatably mounted on the end of said feed pipe, said housing having a transverse nozzle chamber with openings in the sides of said housing; a cage member mounted in said nozzle chamber through said side openings and having wall ports communicating with the interior thereof; a nozzle member having a hollow spindle rotatably mounted in said cage member, said spindle having wall ports communicating with the interior of said cage; means for securing said cage member in said nozzle housing; thrust receiving means for holding said nozzle member against transverse movement in said cage member; liquid sealing means interposed between said spindle and said cage member on opposite sides of said wall ports; means for rotating said nozzle spindle; and means for simultaneously rotating said housing.

14. In a cleaning device of the class described, the combination of: a stationary feed pipe; a housing unit rotatably mounted on the end of said feed pipe, said housing having a transverse nozzle chamber provided with side openings; a bushing member extending through the side openings in said nozzle chamber; a flange on said bushing engaging one face of said housing adjacent one of said side openings; a nut in threaded engagement with said bushing engaging a face of said housing adjacent the other side opening, said bushing having an enlarged chamber provided with wall ports situated within said housing; a nozzle member having a hollow spindle rotatably mounted in said bushing, said spindle having wall ports situated in said enlarged chamber; thrust receiving means interposed between said bushing and said spindle for holding said spindle against transverse movement; means for rotating said nozzle spindle in said housing; and means for simultaneously turning said housing on said feed pipe.

15. In a cleaning device of the class described, the combination of: a stationary feed pipe; a housing unit rotatably mounted on the end of said feed pipe, said housing having a transverse nozzle chamber provided with side openings; a bushing member extending through the side openings in said nozzle chamber; a flange on said bushing engaging one face of said housing adjacent one of said side openings; a nut in threaded engagement with said bushing engaging a face of said housing adjacent the other side opening, said bushing having an enlarged chamber provided with wall ports situated within said housing; a nozzle member having a hollow spindle rotatably mounted in said bushing, said spindle having wall ports situated in said enlarged chamber; thrust receiving means interposed between said bushing and said spindle for holding said spindle against transverse movement, said thrust receiving means comprising a cap plate on the end of said bushing, a pin on said spindle extending through said cap plate, a nut on the end of said pin, and a radial thrust bearing interposed between said nut and said cap plate; means for rotating said nozzle spindle in said housing; and means for simultaneously turning said housing on said feed pipe.

16. For use in a tank cleaning device of the class described, the combination of: a housing having a nozzle chamber provided with side open-

ings; a bushing member extending through said side openings and having a flange engaging the face of said housing adjacent one of said side openings; a nut threaded on said bushing and engaging the face of said housing adjacent the other side opening, said bushing member having an enlarged chamber situated in said housing and provided with ports communicating with the interior of said housing; a nozzle member having a hollow spindle rotatably mounted in said bushing, and radial nozzle means on one end thereof outside of said bushing, said spindle having ports communicating with said enlarged chamber; a pin on the end of said spindle opposite the nozzles on said nozzle member; bearing means on said pin; a cap plate interposed between said bearing means and said bushing; a collar member secured to said bushing and having a portion extending over said bushing; bearing means interposed between the extension on said collar and an annular face on said bushing; means for rotating said nozzle spindle in said housing; and means for simultaneously turning said housing on said feed pipe.

17. For use in a tank cleaning device of the class described, the combination of: a housing having a nozzle chamber provided with side openings; a bushing member extending through said side openings and having a flange engaging the face of said housing adjacent one of said side openings; a nut threaded on said bushing and engaging the face of said housing adjacent the other of said side openings, said bushing member having an enlarged chamber situated in said housing and provided with ports communicating with the interior of said housing; a nozzle member having a hollow spindle rotatably mounted in said bushing, and radial nozzle means on one end thereof outside of said bushing, said spindle having ports communicating with said enlarged chamber; a pin on the end of said spindle opposite the nozzles on said nozzle member; bearing means on said pin; a cap plate interposed between said bearing means and said bushing; a collar secured to said nozzle member and having a portion extending over said bushing; bearing means interposed between the extensions on said collar and an annular face on said bushing; a floating gear mounted on said collar member; a pawl in said gear; ratchet teeth on said collar member adapted to be engaged by said pawl; and power means on said housing for driving said gear and thereby rotating said nozzle spindle in said bushing.

18. For use in a tank cleaning device of the class described, the combination of: a housing; a nozzle member mounted in internal communication with said housing for rotation about an axis normal to the axis of said housing; a hollow boss formed on said housing; a turbine shaft extending through said hollow boss; bearing means in the ends of said boss supporting said turbine shaft; means including conduits in said housing for delivering lubricant into the mid-portion of said hollow boss; oppositely disposed threads on said shaft for conveying said lubricant from the mid-portion of said boss to said bearings; a turbine wheel on one end of said shaft; gear means connecting the other end of said shaft with said nozzle member; and means for directing a power liquid from said housing against said turbine wheel.
